BAG FILLING MACHINE

Albert Krasa, Chicago, Ill.

Application August 9, 1932, Serial No. 623,658

54 Claims. (Cl. 226—48)

One of the objects of the invention is to provide a machine that will fill bags of large capacity with a high degree of accuracy in weights. This is accomplished by using one of the well known 5 automatic scales reputed as weighing charges to within one-fourth of an ounce of accuracy. The weighed charge is dropped gravitationally into a feed pipe having a smooth cone-shaped interior, whence it is completely discharged into a bag.

Another object is to provide a machine that will fill a valve bag supported on a movable carriage, convey the filled bag away from the machine to remove it from its spout, thence discharge it from the carriage in a manner that will seal 15 the bag at the valve.

Another object is to provide a machine that is fully automatic in operation to insure high production and low operating cost. The placement of a bag on the inactive filling spout and applying 20 its respective bag-holder is the only manual labor required.

Another object is to provide a machine the automatic operation of which is automatically stopped by the failure of the machine operator 25 to place a bag on the inactive spout and applying its bag-holder to grip it, during the interval of filling the bag on the active spout.

Another object is to provide a means whereby the trip mechanism of the scale to drop a charge 30 is not actuated when the inactive spout is not provided with a bag in a manner described above.

Another object is to provide a machine having a valve for closing the discharge orifice of the 35 ejector unit, that is normally open during the filling of a bag and is closed during the interval of alternating the spouts, that will prevent the opening of said valve when the inactive spout shifting into filling position is not previously provided with a bag in the regular way.

Another object of the invention is to provide 40 a means that is controlled by the filling material in the feed pipe for actuating the intermittently operated mechanism.

Another object is to provide an improved means 45 for compacting the material in the bag as it is being filled.

Another object is to provide a means for guiding the bottom end of a bag suspended on the inactive spout to bring it over the middle of the 50 bag support when said spout is moved to filling position.

Other objects will appear as the discourse progresses.

In the accompanying drawings which form a 55 part of this specification, Figure 1 is an elevation

of the right side showing a bag in process of filling on the left spout. A portion of the right spout is broken away to show more clearly the bag-holder gripping the bag on the left spout. The crank and connecting rod operating the discharge carriage and the back end of the frame are illustrated broken away, as are also the front ends of the auxiliary base, rails and guard bars for said carriage.

Fig. 2 is an elevation of the right side of the 10 discharge carriage in operation to discharge a bag that was filled on the right spout.

Fig. 3 is a front elevation showing an empty bag on the left spout gripped by the bag-holder and the bag-guide rods. The carriage is returning to filling position after discharging a bag filled on the right spout.

Fig. 4 is a plan view of mechanism below the 20 frame top. The bevel gear cover, discharge carriage and the auxiliary base are removed for the sake of clarity.

Fig. 5 is a front elevation with the front frame removed. The feed-pipe, ejector unit and the electric switch are also removed to expose the mechanism operating back of them.

Fig. 6 is a plan view of mechanism between the 25 arrows 6—6 in Fig. 1 after the bag shown in said figure has been filled and discharged. The operative position of the bag arm 255 is clearly shown supported on a fragment of the right side-plate 30 of the discharge carriage.

Fig. 7 is a vertical cross section of the feed pipe and ejector cylinder to clearly expose the clutch controller pivoting in a recess, the rotating ejector and the leveling propeller.

Fig. 8 is a plan view of the ejector. A fragment of an arm is broken away to expose the front end of the plate 24 overlapped by the arm.

Fig. 9 is a bottom view of the ejector.

Fig. 10 is a perspective view of one of the plates 40 24 on the ejector.

Fig. 11 is a diagrammatic view of a mercury switch adapted for operation by the clutch controller.

Fig. 12 is a side view of the electric switch along 45 the line indicated by the arrows 12—12 in Fig. 7.

Fig. 13 is an elevation looking from the right side of the machine, of the clutch, and solenoid for actuating it.

Fig. 14 is an elevation of the same parts in Fig. 13 looking from the back end of the machine.

Fig. 15 is a cross section of the key and its associated parts along the line between the arrows 15—15 in Fig. 13.

Fig. 16 is a cross section of the parts indicated by the line between the arrows 16—16 in Fig. 14.

Fig. 17 is a plan view of the ejector cylinder, valve support and valve, and the spout carrier, 5 all in cross section along a horizontal line passing through the center of the discharge orifice of said cylinder.

Fig. 18 is a view of the recess formed on the feed pipe looking in the direction of the arrows 10 18—18 in Fig. 3.

Fig. 19 is a view of the shaker operating mechanism looking in the direction of the arrows 15 19—19 in Fig. 1.

Fig. 20 is a cross section of Fig. 22 at 20—20.

Fig. 21 is a cross-sectional view looking from the end of one of the arms 23 of the ejector having the projection 23—B for thrusting material 20 against the controller plate 101—C.

Figs. 22, 23 and 24 are views of the parts looking in the direction of the arrows 24—24 in Fig. 6. Fig. 22 shows the parts in normal position with the left spout in filling position; Fig. 23 illustrates the right spout moved into filling position and the valve-opening pawl 139 diagrammatically disengaged from the valve-operating stud 145 by the rod 196—R; Fig. 24 illustrates the parts at the completion of the operative cycle begun in Fig. 23, leaving the valve closed.

Fig. 25 is an enlarged view of the bag-holders 30 as illustrated in Fig. 1.

Fig. 26 is a cross-sectional view of the feed pipe showing the clutch controller 101—B diagrammatically suspended in the recess of said pipe. A fragment of the cylinder 15 and ejector 35 arm 23 having the projection 23—B are also shown in cross section.

Fig. 27 is a cross section of the plate 144 at the line 27—27 in Fig. 3 to illustrate the recess in the plate.

40 Weighing scale and feed pipe

The weighing scale is conveniently illustrated by a housing enclosing the space occupied by it and is identified by the numeral 1, see Fig. 1. Its upper portion is broken away. It is one of 45 well known types of scales that automatically weighs the material forming a charge and is adapted to discharge the weighed material by manually operating a charge trip device, herein illustrated as a lever. This lever when released 50 by the operator is adapted to return to its normal position. When said lever is held in position to discharge the scale, for a long period of time, it will cause the scale to repeat discharging as fast as the material is weighed. To operate said 55 lever automatically and avoid repetition of discharging by permitting the lever to return immediately to its normal position, the following described mechanism is used:

The manually operated lever described above is 60 displaced by the lever 2. Since the weighing and discharge mechanisms are old in the art they are not illustrated. But to illustrate in a conventional manner the connection of lever 2 with the discharge mechanism within said housing, an 65 oscillating shaft 3 is employed.

Dog 4 is a pivoted extension of the lever 2. It is provided with the tail 5 which is normally held against the underside of stop 6 secured to 70 the lever, by spring 7. It is apparent that when the dog is contacted from above by a moving member the lever 2 is moved with it and when contacted at its underside it alone is moved on its pivot.

75 Lever 8 is pivoted axially parallel to the lever

2. When in normal position, it is pressed against stop 9 by spring 10; and its end 11 is above dog 4 and adapted to contact it. When pulled down by rod 12, the upper end of which is loosely connected to the lever, end 11 of lever 8 contacts dog 4 and swings in its arc of movement about the pivoted center of lever 2 in a sufficient degree to actuate the discharge mechanism of the scale, after which it passes out of the said arc, thereby terminating the contact between it and the dog and permitting lever 2 to be returned to normal position by spring 13.

During the return movement of lever 8 to normal position it contacts the dog on its underside, lifting it sufficiently to pass it. The dog is returned to normal position by spring 7.

The lifted dog and the normal position of lever 8 are diagrammatically illustrated in Fig. 1. Lever 8, as illustrated, is held at its down position by rod 12. The cause for this will be explained 20 later.

The weighed charge of filling material, after it is discharged from the scale is received by the vertically disposed feed pipe which directs it by gravity to a discharging unit for filling receptacles.

Although a one-piece pipe would fulfill its purpose equally as well, the feed pipe is preferably made in two sections 14 and 14A, for convenience in handling to make adjustments and repairs. The sections being suitably connected to each other, the upper or intake end of the feed pipe is connected registrably with the discharge opening provided in the scale in any suitable manner.

The interior of the feed pipe has a gradual outward taper beginning at its intake opening and terminating at its outlet opening thus forming a cone of the filling material which is slightly compacted by the drop from the scale. This is for the purpose of reducing the frictional resistance of the filling material against the wall of the pipe in its passage through it and to reduce to a minimum any possibility of it adhering to the pipe.

45 Ejector unit

The preferred embodiment for discharging the filling material into a receptacle is the conventional ejector type with improvements as noted.

The vertically disposed ejector cylinder 15 is 50 provided with a tangential discharge orifice 16 and a bottom 17. The uppermost surface of the discharge orifice is preferably below the top of the cylinder to provide a continuous wall for the orifice integral with the cylinder.

Vertical shaft 18 operating ejector 22 passes through a central opening in the cylinder bottom and extends upwardly into the feed pipe.

To prevent the escape of filling material and dust through said opening, there are provided a 60 sleeve projecting upwardly from the cylinder bottom and a stuffing box 20 projecting downwardly from it.

The top end of the cylinder is closed by a cover 21 having a central intake opening. The 65 cover is suitably connected or united with the bottom end of the feed pipe with their respective openings in register. It is illustrated cast to the pipe. Cover 21 is preferably made with a projection at its bottom side, fitting closely the 70 bore of the cylinder and extending to the uppermost surface of the discharge orifice.

Ejector 22 operating in the cylinder between cover 21 and cylinder bottom 17 is secured to the 75 revolving shaft 18. It is comprised of a hub

having a plurality of radial arms 23 projecting horizontally therefrom, and bottom plates 24.

Ejector arms 23 are preferably made with their front sides 25 vertically disposed and tangent to the hub. The concave surface 26 milled on each of the front sides extends inwardly from the end of the arm to as far as the milling cutter will permit. Its purpose will be explained later.

The back side or shield 27 of each arm slopes rearwardly from the top side terminating at the gap side 28 of the arm for the purpose of shielding the front edge 29 of the plate 24 from material gravitating to the ejector. The bottom side of each arm is provided with a seat 29 extending the length of the arm to which the plate 24 is secured. Projecting to the rear of the seat is the gap side 28 of the arm.

When secured to arms 23 the plates 24 constitute the bottom of the ejector 22 for carrying the filling material gravitating from the feed pipe. Each plate projects forward from its seat 29 with its front end below the arm in advance, thus forming a gap between them, Fig. 7. The forward end of each plate is inclined toward the cylinder bottom 17 till the front edge 29 is in very close proximity to it. This is for the purpose of scooping up the material that has leaked down on the cylinder bottom, and returning it to the upper side of plate 24.

Because of the overlapping of the arm past the front end of the plate 24 to its rear and because the material on said plate, from centrifugal force generated by the high speed of the ejector, is held toward the front side 25 of the arm supporting said plate, leakage of material through the gap is impossible.

In the foregoing description there are provided four gaps for an ejector having four arms. In use with some materials, there is an advantage in having only two gaps for an ejector having four arms. This is accomplished by spanning two of the arms with a single plate.

In operation, the ejector 22 revolves at high speed. Because of it the filling material entering the cylinder 15 is violently contacted by the front sides 25 of the arms 23 and is compacted toward their middle by the concave surfaces 26. This increases the efficiency of the ejector since the discharge orifice being preferably round, provides more opening across its middle for the discharge of material.

Frame and drive shaft assembly

Frame top 32 provided with an opening for receiving the stuffing box 28 supports the cylinder 15 of the ejector unit.

Frame top 32, side frames 33, 34, 35 and 36, and base 31 are suitably secured to each other forming a dustproof housing for mechanism operating therein.

The right frame 36 is positioned inwardly away from the right ends of frames 33 and 34 to permit driving the discharge carriage from outside of said frame.

Cover plate 38 closes an opening in frame 34 through which the mechanism operating in the housing is oiled and adjusted.

Operating in bearing 39 secured to an extension 37A of base 31 and bearing 40 mounted on 37, the main shaft 41 drives shaft 18 by bevel gears 42 and 43. Bearing 40 is illustrated in Fig. 5 with a portion of its support broken away to clarify the mechanism back of it.

A cored opening in frame 38 provided for shaft 41 is closed by plate 44 to keep out dust from

said housing. A reamed hole in said plate freely receives the shaft.

A pulley 45 drives the shaft 41 from a source of power by a belt.

Bearings 46 and 47 having keyways 48 cut in their clamping surfaces are secured to frames 33 for supporting shaft 18. Similar keyways are cut in said frame opposite to those on said bearings. Keys 49 inserted in keyways 48 are for the purpose of assembling the bearings in exact alignment after removal for repairs.

A ball thrust bearing 50 supported by collar 51 is used on the vertical shaft 18 to carry its weight against the lower bearing 46.

Bevel gear cover 52 is made in halves as illustrated by the section broken away from the front half. The halves when secured together are supported by bearings 48 and 46 on their exterior surfaces adjacent their ends. Set screws secure the cover to the bearings.

The speed-reducing unit 53 is of the conventional gear type for reducing the main shaft speed to a speed suitable for driving the intermittently-operated mechanism and the continuously operated shaker mechanism.

Secured to shaft 41, the spiral gear 54 in mesh with gear 55 operates shaft 56. Sprocket 57 driven by shaft 58 of reduced speed revolves the clutch engagement disc 64 by the sprocket 59. A roller chain 60 connects the sprockets.

Clutch unit

The clutch unit is an improved design of one of the many conventional intermittent clutches developed for revolving a given shaft once for each engagement thereof.

Cam shaft 61 rotating in bearing 62 mounted to base 31, and bearing 63 provided on frame 36, supports the continuously revolving clutch engagement disc 64 having the hub 65 upon which the sprocket 59 is securely mounted.

Along the periphery of the disc are a plurality of notches 66 cut across its width for freely receiving the engaging key 67. The side of the notch in advance of the driving side is given a bevel 68 to permit the gradual entrance of the engaging key into the notch.

Member 69 secured to shaft 61 resembles a webbed iron belt pulley having a flange 70 and a rim 71 illustrated with a portion broken away. Integral with said member is the support 72 for the engaging key 67 extending from the outer edge of rim 71 to close proximity of engagement disc 64. Key 67 is slidably held in support 72 by plate 73 secured to the support.

An elongated opening in the bottom of the support extending inwardly from its end adjacent to the engagement disc 64 is provided to admit stop pin 74 pressed in the key, Fig. 15. Bumper 75 is integral with rim 71 and supports head 76A of the key when engaged by stop lever 76 to stop the cam shaft 61. The flange 70 supports the stop lever against side thrust when disengaging the key from engagement with disc 64. Notch 77 cut across the flange 70 is engaged by detent 78 pivoting on the shaft 64 to prevent reverse movement of cam shaft 61.

The engaging key 67 is preferably made of steel and with a square body provided with a head 76A at one end. The head is under-cut at 70 side 78. The key is pushed into one of the notches 66 of the engagement disc by a compression spring 80 carried in a drilled hole in the key. The outer end of the spring is supported by plate 81 which is secured to support 72 for 75

the key. Stop pin 74 limits the movement of the key 67 when pushed by spring 88 by contacting the engagement disc 64 at its side. When in this position the undercut side 78 of the head 5 of the key is away from the plane of flange 78 sufficiently to permit entrance of the knife edge 82 of stop lever 76 between it and the flange.

Mounted to base 37 bearings 83 support the pivotal shaft 84 of stop lever 76.

10 Stop plunger 85 slidably supported by bearing 76A is cushioned by spring 86, bearing against stop collar 87, which is pinned to the plunger. The bottom end of the plunger extends below the collar to hold the spring in place. The lower 15 end of spring 86 is supported in place by a flanged stud 88 secured to the stop lever.

Bumper-head 89 rigidly secured to stop plunger 85 receives the blow of member 89 in stopping cam shaft 61 by engagement with the head 67A 20 of the key. The bumper-head is sufficiently away from the bearing 76A to permit compression of the spring 86 when the said shaft is stopped, thereby reducing the shock to the parts involved. The bumper-head is preferably square in shape 25 with one side freely abutting the same side of the stop lever in contact with the head 67A of the key when said key is fully disengaged.

The upper end of the stop lever is wedge-shaped for withdrawing the key 67 from engagement with the disc 64 at the completion of one revolution of the cam shaft 61. The operative side of the wedge-shaped end of the lever is provided with a transverse taper 79A (see Figure 16) that conforms with the under-cut side 78 of the 35 head 67A of the key to positively hold the stop lever in place during the withdrawal of the key 67 from the disc regardless of the strain applied to it.

40 Arm 90 operates stop lever 76 to disengage it from the key-head 67A. The operative end of said arm is bifurcated, across the opening of which a pin 91 is secured for operative engagement with trip bar 92. Pin 93 similarly secured, prevents derangement of the trip bar with 45 said arm.

Trip bar 92 is pivotally supported in the slotted end of the vertically disposed plunger 84 which is upwardly actuated by solenoid 85.

50 Notch 96 is cut in the trip bar for hooking the pin 91 whereby the stop lever 76 is disengaged from key 67 when plunger 94 is actuated. A spring 97 resiliently presses the trip bar against 55 pin 91.

Stud 98 is secured to the trip bar and is adapted for operative contact with the cam 99 after the trip bar 92 is lifted by the actuated plunger 94.

Cam 99 is securely held to the outer edge of 60 rim 71 and is adapted to contact stud 98 on the lifted trip bar 92, whereby the trip bar is disengaged from pin 91 to permit the return of stop lever 76 to disengage the key 67 at the completion of one revolution of cam shaft 61.

Spring 100 presses detent 78 and stop lever 65 76 into their respective engaging positions. The spring is hooked to the parts across the space between them.

The operation of the clutch begins with the actuation of the plunger 94 by the solenoid 85. 70 The trip bar 92 being in hooked engagement with the pin 91 at the notch 96, is pulled up with the plunger, whereby the stop lever 76 is moved out of engagement with the engaging key permitting the key to engage one of the notches 96 in the 75 continuously revolving disc 64. Before comple-

tion of one revolution of the shaft, cam 99 disengages the trip bar 92 from pin 91, whereby the stop lever 76 is released and returned against the face of rim 71 by the spring 100, in position to disengage the key 67 from the revolving disc 64 5 and stop the shaft by the engagement of bumper-head 89 with the head 67A of the key.

The clutch controller unit

The clutch controller 101 operating in the section 14A of the feed pipe is preferably a ring supported by a shank having a top surface 101A that will shed the filling material on it after the controller has moved out of the material being discharged. The annular concave groove 102 at the bottom of the ring, illustrated at the broken section (Fig. 7), lightens and strengthens the ring because of its channel-like construction.

10 Sidewalls 103 of a recess provided in the feed-pipe support bearings 104 for a pivoting shaft 105 to which the shank of the controller is secured. Said bearings are preferably bushings having longitudinal secured adjustment in walls 103.

15 A stop lug 106 on said shank contacts the wall of the feed pipe to limit the downward movement of the controller as indicated by the dotted lines, Fig. 7.

20 When the charge of filling material is extremely heavy it is better to eliminate the stop 106 and provide a stop stud fixed to the wall of the pipe diametrically opposite to the pivotal shaft of the controller and adapt the controller for contacting it for the downward stop. This would support the controller against the heavy thrust of the dropped charge on it.

25 Felt washers 107 are interposed on the shaft between the sides of the shank of the controller and the inside ends of bearings 104 for preventing leakage of dust and material from the feed pipe into the bearings.

30 Shaft 105 extends past the outer ends of said bearings. A collar 108 is secured to one end of the shaft and socket 109 at the other end.

35 Switch rod 110 is made of material suitable for completing an electric circuit through it and is secured to the socket 109. A fibre bushing 113 insulates the rod from the socket. The downward movement of the rod is stopped by 115 which is insulated to prevent grounding of the circuit.

40 Switch clips 112 made of resilient, electrical conducting materials are terminals of an electric circuit which is operatively completed by contact of the rod 110 with both clips, Fig. 12.

45 Mounted suitably on frame top 32 a fibre block 114 supports the insulated clips in staggered relation to facilitate cleaning their contacting surfaces.

50 Weight 111 having a slidably secured adjustment on switch rod 110 counteracts the gravity of controller 101 and causes the rod 110 to close the said circuit. The controller is in normal position 55 when the said rod is against the stop 115.

The above described method of completing the circuit is sometimes objectionable because of a spark that may be produced at the clip in breaking the circuit. In such cases the mercury switch 65 is employed (Fig. 11), the description of which follows.

A container 116 for holding the mercury is clamped to rod 110 with a fibre bushing 117 interposed for insulation. A portion of the clamp is illustrated broken away to expose the bushing. An opening at the outer end of the container is closed with a threaded plug 116A to seal it. A flange-headed stud 118 is secured to the plug with its head inside the container.

75

The outer end of the stud is connected with one of the wires of the circuit. The other wire is connected with the container at its clamp screw. The stud and container, thoroughly insulated from each other and from the machine, constitute the terminals of the electric circuit.

With the mercury switch, the rod 110 is preferably a tube for carrying the insulated electric wires which enter it through a hole in the socket 109.

The container is partially filled with mercury 118, which operatively completes the circuit by gravitating into contact with stud 118 when rod 110 is turned downwardly by weight 111 because of it overcoming the gravitational pressure of the filling material on the controller 101. The downward movement of the switch rod is stopped by the stop rod 120 which is suitably supported on frame top 32 and preferably insulated therefrom.

When the controller 101 is thrust to its down position by a charge of filling material, rod 110 is turned upwardly, as indicated by the dotted lines (Fig. 11), to a position causing the mercury to gravitate away from contact with the stud 118, breaking the circuit.

The conventionally illustrated solenoid 95 having the plunger 94 is connected in the aforesaid electric circuit and is of the conventional type for operating the plunger in a single direction, preferably an upward one, as illustrated. When the circuit is automatically broken by the rod 110, the plunger 94 is returned to normal position by gravity or by a spring.

The solenoid is secured to the bracket 121 which is mounted to the base 37 and adapted for use as a guard about the clutch unit.

Fig. 3 illustrates the service wires providing the current to the said circuit, broken off below the hand switch which is secured to the frame 33. The hand switch disconnects the current from the circuit when the machine is not in operation.

In operation, a charge of filling material dropped from the scale into the feed pipe thrusts the controller from its normal position, downwardly, to be stopped by its stop lug 106, contacting the wall of the feed pipe. It is held in this position, in a buried state, by the material above it gravitating to the discharging unit. Because of the thrust given the controller, the electric circuit is sharply broken.

When the material above the controller is reduced by ejection to a predetermined depth, the counteracting weight 111 returns the controller to its normal position, thereby completing said electric circuit to actuate said intermittent clutch.

It is preferable to have the depressed controller in close proximity to the ejector. When the counteracting weight 111 returns it to normal position, the action at the beginning is slow. Because of this slowness, together with that of the cam shaft 61, the rapidly revolved ejector completely discharges the material of a charge into the bag before the valve 142 closes the discharge orifice 16.

Because the conventional automatic scale is very accurate in weighing a charge, and because the charge dropped from the scale into the feed pipe is completely evacuated from it and the ejector, very accurate weights in the filled bag are assured.

Clutch controller, force operated

The preferred embodiment of another form of clutch controller that is operated away from its

normal position by a mechanically produced force, is illustrated in Fig. 26. A detailed description of it follows.

The feed pipe and ejector unit in the foregoing description are used with changes as here noted. A fragment of each is illustrated in cross section.

The clutch controller 101—B operating suspendedly in a recess projecting from the interior of the feed pipe is comprised of a plate 101—C 10 having a shank for supporting it from the shaft 105—B. The shaft 105—B is pivotally supported in the same manner as that illustrated in Fig. 18.

The recess extends downwardly in a vertical manner to the ejector 22. The wall of the feed pipe at 14B extends below the top end of the recess forming an inclosure for protecting the shaft 105—B from material in the feed pipe. An opening at the top end of the recess, provided for making adjustments of the parts assembled on said shaft, is closed by a cover plate 303—B.

Switch rod 110—B suitably secured to shaft 105—B is operated by said controller to open and close an electric circuit. It is preferably a tube so that an insulated wire for conducting an electric current to contact point 311 can be carried in it. Point 311 is insulated from the rod and secured thereto in any suitable manner.

Contact point 312 illustrated in contact with point 311 is fixed to an end of a resilient strip 313 of electrical conducting material. The other end of said strip is fixed to a bracket 314 which is mounted in an insulated manner to the feed pipe. Points 311 and 312 are terminals of the aforesaid electric circuit in which the aforesaid solenoid is connected.

When the stop 101—D, provided on the shank of the controller, is in contact with the wall of the feed pipe at 14B the controller 101—B is in normal position.

The weight 111—B secured to rod 110—B counteracts the gravity of the controller to keep it in normal position when the feed pipe is empty, thereby causing a contact between the points 311 and 312. The pressing contact between the points is regulated by the adjustment of the weight on the rod 110—B.

A projection 23B having a front side 26B that inclines forward from the front side 25 of the arm 23, is provided on each of said arms of the ejector 22. The front sides of said projections are inclined just enough to provide a constant supply of material to the ejector unit. A cross section of an arm and said projection is illustrated in Fig. 21. The projections operate in the opening provided at the bottom end of the feed pipe which is, in fact, the intake opening of the ejector cylinder 16. The plate 101—C of the controller is positioned opposite to the path of the rotating projections.

When a charge of filling material is dropped into the feed pipe, the projections operating continuously at high speed violently thrust material against the plate 101—C of the controller. The force exerted by the thrust material sufficiently overcomes the gravity of the counteracting weight 111—B to cause the controller, in its forced movement away from normal position, to sharply break the electric circuit at the points 311 and 312. The positions of the controller and said points are diagrammatically illustrated in Fig. 26.

The continuous thrust of material during the ejection of a charge from the feed pipe keeps the controller away from normal position until the

material above the ejector 22 is so reduced in quantity that the force resulting from the thrust is insufficient to overcome the gravity of the weight 111—B, wherupon the controller is returned to normal position and the electric circuit completed.

With this type of controller the leveling propeller 122 and the apparatus for delivering compressed air to the recess is not required.

10 By eliminating the projections 23B, the controller 101—B can be actuated by the side pressure of the material in the feed pipe.

Leveling propeller

15 Above the controller in its normal position, the leveling propeller 122 is suitably fixed to the end of the ejector shaft 18. In principle, it is similar to a ship's propeller. It thrusts the material of the charge toward the ejector unit by its downwardly inclined faces 123 and levels off the top surface of the material when said surface is approximately at the same height of the leveling propeller. The feed pipe, in Fig. 1, is broken away to illustrate this feature.

25 The unevenness of the top surface of the filling material, as it may be before it is leveled, is indicated by the broken line 124, Fig. 1. The rotating propeller fitting closely to the wall of the feed pipe undercuts the material of the high side 30 when the low side is approximately even in height with the propeller. The undercutting causes the material to be violently dashed about, filling the hollows in said top surface. This action is continued until the top surface is lowered by ejection, even with the low side of the propeller, at which position the propeller gives the material a scraping action, producing an even and level surface on the material.

The propeller 122 also performs the function of 40 breaking up the lumps that may be in the material by its high rotating speed.

Valve-operating mechanism

45 The valve mechanism for closing orifice 16 is actuated by cam 125 secured to shaft 61. It operates a vertical shaft 126 by lever 127. Roller 128 operating in the groove of said cam is supported by lever 127. The projecting end of shaft bearing 63 abuts the cam at a recess provided to receive it.

50 Bearing 129 mounted to base 37 and bearing 130 provided on frame top 32 support shaft 126 which is provided with a ball thrust bearing 131 for carrying its weight. A collar, not illustrated, 55 abuts the lower end of shaft bearing 130 to prevent end movement of the shaft.

Rock shaft 132 having operating lever 133 is operated from shaft 126 by the lever 134. Lever 133 extends upwardly from the rock shaft through 60 a cored opening in frame top 32.

A connecting rod 135 provided with a ball joint at each end connects levers 133 and 134. The length of the rod is adjustable to position the discharge opening 142—A in valve 142 in register 65 with discharge orifice 16.

Bearing 136 mounted to frame top 32 and bearing 137 on frame 33 support the rock shaft 132 having a lever 138 for operating pawls 139 and 140. Both pawls are pivoted to lever 138 at 70 141. End movement of rock shaft 132 is prevented by lever 133 and a collar abutting the ends of bearing 136.

A plate valve 142 operating slidably in a guide-way in valve support 143 closes the discharge 75 orifice 16 before spout carrier 156 is shifted to

alternate the spouts. It is opened when the inactive spout having a valve bag gripped by the bag-holder is shifted to filling position by the spout carrier, and the discharge carriage returned to support said bag. The valve is normally open when the discharge opening 142A provided therein is in register with said orifice. It is held in the guideway by plate 144 secured to the valve support.

Valve support 143 extending horizontally past 10 the discharge orifice 16 is cast integral with cylinder 15 at the outer end of said orifice. It is provided with an elongated opening in said extension through which the valve-operating stud 145 passes. The said stud is rigidly secured to 15 the valve.

The valve is opened by pawl 139 in engaging contact with stud 145. It is closed by pawl 140 in engaging contact with the opposite side of the 20 stud.

When the valve is in closed position the pawl 139 is adapted to be lifted out of engagement with the stud 145 under a condition to be explained later. When thus disengaged, both pawls are 25 out of engagement with said stud in the valve-opening movement of the operating lever 138.

When the pawls are in operative engagement with stud 145 they are supported in position against gravity by it. When out of engagement, they gravitate to the stop plate 146 secured to support 143, Fig. 24. Ends 147 of both pawls are inclined forwardly to lift the disengaged pawls gradually into engagement with the stud. Where conditions require it, the pawls can be resiliently 35 pressed to stud 145 by springs arranged on the lever 138.

The upwardly extended arm 139—A of pawl 139 has a laterally projecting lug 148 provided with outwardly inclined extensions 149 and 150 for 40 the purpose of disengaging the pawl from the stud 145.

Strap 151 supports the arm 139—A against side thrust when the pawl is being lifted out of engagement. The strap is not illustrated in the 45 general assembly views.

Under normal filling conditions the valve is used primarily to prevent the exhaust of dust from the ejector unit into the air during the interval between the removal of the filled bag off its spout and the completion of movement to shift the inactive spout into filling position. It can also be used to cut off the filling material being ejected into a receptacle when the controller is positioned so high above the ejector 22, 55 that if all of the material in the feed pipe were ejected into said receptacle an overweight would result.

A shaft 152 pivoting in bearing 153 supports levers 154 and 155 for operating lever 8 mounted 60 on the scale. Lever 154 is adapted to contact stud 145 when the valve is being opened, whereby the scale is tripped to drop a charge.

Normally when the valve is opened, the lever 154 remains in contact with stud 145 until the 65 valve is closed again. Because of it, lever 8 on the scale is held to its down position during the filling of a receptacle.

Spout carrier mechanism

70 Spout carrier 156 is slidably held against plate 144 by dove-tailed guide bars 157 and 158. Cap screws secure the guide bars and plate 144 to valve support 143.

The spout carrier is provided with two filling 75

spouts 158 and 158R which are alternated into register with discharge orifice 16 of the ejector unit. The mechanism operating it follows.

Cam shaft 61 operates cam 160 on the shaft 5 161 by bevel gears 162 and 163 at one-half its operating speed. Cam 160 shifts spout carrier 158 to move the inactive spout to filling position at each engagement of the aforesaid clutch.

Bearings 164 support shaft 161, end movement 10 of which is prevented by gear 163 and a collar, not illustrated, abutting the ends of the bearing.

Rock shaft 165 having operating lever 166 is 15 oscillated by lever 167. It is illustrated in Fig. 5, broken off. Roller 168 operating in the groove 15 of cam 160 is mounted on lever 167. Connecting rod 169 connects levers 166 and 167.

Lever 167 is supported by shaft 170 pivoting in bearings 171 which are mounted to base 31. The said lever and a collar 172 abut the inside ends 20 of the bearings to prevent end movement of its shaft.

Rock shaft 165 pivots in a bearing provided in the support 173 and bearing 174 on frame 33. The support 173 illustrated in cross section in 25 Fig. 4 is mounted to frame top 32.

Lever 175 operates the spout carrier from rock shaft 165 by the connecting link 176.

Spout carrier locking mechanism

30 Spout carrier locking block 177, clearly illustrated in Fig. 20, secures the carrier firmly against plate 144 after it is shifted to alternate the spouts. It is operated by lever 178 which in turn is actuated by cam 179 secured to shaft 35 126.

Lever 178 pivots on a stationary stud 180 mounted suitably on frame top 32. It is provided with a roller for contacting the cam.

One end of the connecting rod 181 passing free- 40 ly through openings in valve support 143 and plate 144, is suitably secured to the block 177. The other end is provided with a threaded socket having a bifurcated end which pivots on lever 178. Adjustment for the locking block is had at the 45 threaded socket. A lock nut secures the adjustment.

Locking block 177 operates in a notch machined in guide bar 157, Fig. 20. In operation, it functions as a wedge between the guide bar and the carrier 156. Because of excessive wedging angle, the grip of the block on the carrier is released when its cam 179 is moved to inoperative position.

Plate 144 with recesses

55 Plate 144 is provided with an opening registering with discharge orifice 16 and recesses 182 extending to the bottom edge of the plate. The recesses having sharp, vertically disposed corners are juxtaposed to the back side of the spout carrier 156 for removing the fine particles of material lodged on said carrier during the filling operation, by a scraping action produced by the moving carrier in contact with the said corners. Figs. 17 and 27 clearly illustrate said recesses.

65 Similar recesses, not illustrated, in the valve support 143 are juxtaposed to valve 142 to prevent troublesome accumulation of material in the guideway.

Bag holding mechanism

70 Each filling spout on carrier 158 has an individually operated bag holder that is of a conventional type for gripping a bag with an effectiveness that increases proportionately with a 75 force tending to remove it from the spout.

Bag holders 183 and 183R having serrated bag-holding surfaces 184 are pivotally supported on a fixed shaft 185 carried by bracket 186 on spout carrier 158.

80 Springs 187 hold the bag holders in gripping contact with valve bags placed on their respective spouts by an operator. Handles 188 and 188R are for manually applying the holders to said bags to check the pull of said springs and for making adjustments of said bags on the 10 spouts.

Latches 189 and 189R respectively pivoted to the bag holders at 180, operatively engage their respective pins 191 whereby the bag holders are held away from their respective spouts to permit 15 the placement of valve bags thereon.

182 resiliently press the latches into engagement with their respective pins 191 which are secured to bracket 186.

Integral with their respective latches the manually operated trip fingers 193 and 193R disengage the latches from their respective pins 191.

194 Latch stops contact the bag holders to limit the movement of their respective latches pressed 25 by their springs 182.

Each bag holder is provided with a convex projection 195 that is operatively engaged by the end 200A of the push rod 200 to remove the bag holder from the bag after it is filled and to 30 move it into latching engagement with its pin 191. The bag holder is thus latched during movement to alternate the spouts and remains thus until manually disengaged.

Rods 196 and 196R are slidably supported in 35 bearings 197 and 197R provided on spout carrier 156. Each rod is operated by a bag holder. The links 198 and 198R connect the bag holders with the rods.

Rods 196 and 196R are for the purpose of dis- 40 engaging pawl 199 from stud 145 to prevent the automatic opening of valve 142 and to prevent the tripping of the scale to drop a charge into said feed pipe, when the bag holder of the spout being moved into register with said orifice is 45 engagedly latched to its respective pin 191.

Normally, the empty bags are placed on the spout and the bag holder applied by the machine operator during the interval of filling the bag on the other spout. The bag holder thus 50 applied moves its respective rod out of operative engagement with the lug 148.

After a bag is filled the bag holder gripping it is automatically latched to its pin 191, thereby 55 moving its respective rod into position to engage lug 148 in the next movement of said carrier to shift the spout of said latched bag holder into filling position. If the said latched bag holder is undisturbed before the next movement of said carrier to shift its spout into filling position, its respective rod is moved by the carrier into contact with its respective inclined extension (149 or 150) of the lug 148, thereby lifting the pawl 199 gradually out of engagement with stud 145, after which the rod slidably supports 60 the lug 148 in lifted position to prevent engagement of the pawl with said stud during movement of the lever 198 to open said valve. This is diagrammatically illustrated in Fig. 23.

65 By thus disengaging the pawl 199 from the 70 valve operating stud 145, the discharge orifice 16 remains closed after the said spout having the said latched bag holder is moved into register with said orifice and the charge in the scale is prevented from dropping since its discharge 75

mechanism is actuated only when the valve is moved into open position. This is for the purpose, in the case of failure to place a bag on the spout during the interval of filling a bag on the other spout, to prevent the discharge of material onto the floor when said spout is moved in the filling position, and to stop the continuous automatic operation of the machine, which depends on the dropping of the charge in the feed pipe in timed relation with the intermittently operated mechanism.

To resume the automatic operation of the machine after it is stopped by the aforesaid condition, a bag is placed on the spout which is now in filling position and its bag holder applied to grip the bag. The valve 142 is then manually moved by the valve extension 199 into open position, thereby causing the stud 145 to be in operative contact with the pawls 139 and 140 and causing the actuation of the discharge mechanism of the scale to drop a charge.

Where conditions do not require a valve to close orifice 16, the scale is prevented from dropping a charge by a movable member which is adapted for operation by pawls in a manner similar to that of the valve in the foregoing description, and which is provided with means to engageably trip the scale.

Push rod mechanism

20 Push rod 200 is slidably supported in bearings on bracket 201 which is secured to lug 202 projecting from cylinder 15.

25 Cam 203 secured to 61 operates push rod 200 by the following intermediate mechanism.

A bell crank having levers 204 and 205 pivots on a shaft that is supported from base 37 by a bracket 206. The cam actuates lever 204 by a roller 207 which is held in pressing contact with it by spring 208, Fig. 4.

40 Rock shaft 209 provided with operating lever 210 is operated from lever 205 by the connecting rod 211. It oscillates in a bearing provided in support 173, and bearing 212 provided on frame 38.

45 Stub shaft 213 pivoting in bearing 214 is operated from shaft 209 by levers 215 and 216. A connecting rod 217 connects the levers. Figures 4 and 5 illustrate the rod, broken off.

50 Fixed to the stub shaft, the lever 218 operates 200 by a bifurcated connecting link 219. Levers 216 and 218 abut the ends of bearing 214 supported by bracket 201.

Discharge carriage assembly

55 The discharge carriage supports the bag during the filling operation after which it conveys the filled bag away from the machine to discharge it. The description of the discharge carriage assembly follows.

60 The auxiliary base 220 is suitably secured at one end to the main base 37. The opposite end is secured to the floor in a substantial manner.

65 Rails 221 secured to base 220 substantially parallel with the axial line of discharge orifice 16, support frame 222 of the movable carriage by flanged wheels 223 which are journaled on flange-headed studs 224 secured to the frame.

The carriage is operated by crank 225 rigidly secured to shaft 61, abutting shaft bearing 63. Connecting rod 226 connects the crank with the bifurcated lug 227 projecting upwardly from the carriage frame 222. It operates through a cored opening in the front frame 33.

70 75 Wheels 223 are provided with outwardly pro-

jecting bosses 228 which operate in close proximity to guard bars 229 and 230—A to prevent derangement of the carriage with the rails. Brackets 230 secure the guard bars in parallel alignment with the rails to base 220—illustrated 5 abutting the sides of the rails.

Lugs 231 and 231A projecting upwardly at the front end of the frame have a plurality of spaced splines 232 cut horizontally across their front surfaces in longitudinal alignment. The base of 10 the bag support bracket 233 is provided with a pair of feathers 234 in longitudinal alignment which are spaced apart to respectively fit in one of the splines of each lug, for maintaining its horizontal alignment throughout the range of 15 adjustments on said lugs. Provision is made to secure bracket 233 at each adjustment. The adjustment of the bag support bracket is necessary to fill bags having a wide range in lengths.

Bearing 235 on said bracket pivotally supports 20 shaft 236 to which one end of bag support rocker 237 is secured. The opposite end of the rocker is engagingly operated by the shaker arm 238 during the bag filling operation. Collars 239 abut the bearings to prevent end movement of 25 shaft 236.

Shaker arm 238 is provided with a roller 240 for operative contact with a hardened plate 241 secured to the under side of the rocker 237. In cases where a high operating speed of the shaker 30 arm is required with a minimum operating noise, the rocker is suitably bifurcated to closely receive roller 240 of the shaker arm.

By the movement of the carriage to discharge the filled bag the rocker 237 is moved out of engagement with roller 240 of the shaker arm whereupon the rocker 237 gravitates to stop pin 242 which is adjustably secured to frame 222.

Provision is made at 243 and 244 for up or down adjustments of the bag support 245 on the 40 said rocker to suit bags of varying lengths within a close range.

45 Rocker 237 is provided with the discharge operating arm 246. When the carriage is moved a predetermined distance to discharge the filled bag thereon, arm 246 engages the rotably secured roller 247, causing the bag support 245 to be upturned quickly, whereby the said bag is tilted from the carriage with a slight thrust at the completion of said discharging movement. The thrust given to the tilted bag causes it to be partially upset when it strikes the means for receiving it—usually a moving conveyor. The impact of the fall causes the material to be thrust against the flap of the valve on the inside of 55 the bag, thereby sealing it.

The threaded stud 248 supporting roller 247 at its bifurcated end has vertical adjustment at the elongated opening in the upwardly projecting lug 249 on base 220. Longitudinal adjustment of the stud is had by threaded nuts which secure it to the lug.

When the carriage is returning from discharge, the bottom end of the bag on a spout moved into filling position enters a channel 250 provided in 65 the middle of the bag support 245. The channel is flared outwardly at 251 to facilitate the entrance of the bag.

A wall 252 across the front end of the bag support prevents the filled bag from sliding off the 70 support during movement to tilt it, Fig. 2.

Carriage side plates 253 and 254 provided with lateral adjustment to suit filled bags of various thicknesses, are secured to the top side of frame 222. Suitably reinforced with ribs, the side plates 75

prevent the filled bag from falling sideways during the discharge movement.

Bag arm 255 is secured to the shaft 256 pivoting in bearings 257 on side plate 254. In operative position the arm extends horizontally past the rear end of the filled bag adjacent to the spout to remove it therefrom by a pressing contact caused by the discharging movement of the carriage.

Lever 258 secured to shaft 256 is engagingly operated from contact with stud 259 fixed to the operating lever 260. Operating lever 260 is freely mounted on said shaft abutting the bearing and lever 258. Collar 261 abuts the other bearing to prevent end movement of shaft 256.

Connecting rod 262 connects lever 260 with cam lever 263. It is made adjustable to set stud 259 in exact relation with contact lever 258.

The cam lever is pivotally mounted on lug 231-A. It has the roller 264 for engaging the cam 265 secured to the guard bar 229-A.

In the discharging operation the bag arm 255 remains in operative position after the filled bag is removed from its filling spout until the carriage begins to tilt the filled bag, at which time the cam lever roller 264 engages cam 265, whereby the bag arm is turned downwardly to engage pawl 266.

Bearing 267, suitably mounted on side plate 254, supports the pivoting shaft of pawl 266. The pawl is resiliently pressed into engagement with the bag arm by spring 268. When out of said engagement its movement is stopped by 269 coming into contact with 254. The pawl is disengaged from the bag arm by lever 270 which is secured to its pivotal shaft.

During the return movement of the carriage to filling position, the bag arm is held by the said pawl to permit the entrance of the bag suspended on a spout in filling position. During the same time the levers 260 and 263 connected by 262 return to normal position by gravity.

At the completion of said movement the bag arm is released from pawl 266 by lever 270 coming into engaging contact with the flanged head of pin 271 which is adjustably secured to frame 33. After the bag arm is released it is returned to operative position by spring 272.

Reverting back to the discharge of the filled bag, it is sometimes more desirable to slightly upturn the bag support 245 shortly after the beginning of the discharging movement to relieve the spout of any bag strain that may be on it, thereby facilitating the removal of the bag from the spout. This is accomplished by providing the arm 246 with a roller which contacts a cam-shaped bar secured to the base 220. The bar is shaped so as to give the bag support the desired lift during the removal of the bag off the spout, after which it is shaped to complete the upturning movement of the bag support to discharge the bag.

When said arrangement is used, lug 249 and stud 248 supporting roller 247 are eliminated.

Bag guide rod assembly

The filling spouts on carrier 156 are spaced apart so that when one of them is in filling position, the other is sufficiently outside of the vertical plane of one of the carriage side plates (253 or 254) to conveniently suspend a bag from it. A bag thus suspended is indicated by dotted lines in Fig. 3 with its upper end broken away. The bag hangs between the side plate and its respective guide rod 273 in normal position which is indicated by dotted lines in the same figure.

When the carrier 156 is operated, the spout

having an empty bag suspended thereon is shifted toward filling position when the carriage, in its movement to discharge the filled bag, is a suitable distance away to clear said suspended bag. Fig. 2 clearly illustrates this feature. The lower end of said shifting bag is moved relatively with its spout by the guide rod 273 contacting its outer side wall. When said spout is finally in filling position, both guide rods, moving simultaneously toward each other, grip the bag to guide its bottom end into channel 250 of the bag support during the return movement of the carriage. Fig. 3 illustrates a portion of the wall 252 broken away to expose this feature more clearly.

Just before the carriage is returned to filling position, the guide rods return to their normal position passing through openings 274 in the carriage side plates 253 and 254.

The guide rods are carried by levers 275 and 276 having segmental gears 277. Lever 276 is 20 pivotally mounted at 278 on frame 33. It is operated by its segmental gear in mesh with that on lever 275 which is operated by shaft 279.

Bearing 280 provided on frame 33 and bearing 281 supported on frame 36 support the said shaft 25 having the operating lever 282.

Connecting rod 283 connects lever 282 with lever 284 of a bell crank. It is provided with a ball joint at each end.

The said bell crank is freely mounted on the same shaft that supports the bell crank having the levers 204 and 205. The other lever 285 of said bell crank supports a roller 286 which is in operative contact with cam 287 secured to shaft 61.

Spring 288, hooked at one end to lever 275 and its other end to a pin on frame 33, presses roller 286 against cam 287.

Shaker mechanism

Shaker arm 238 is adjustably secured to the reciprocating bar 289 in relative position with bag support bracket 243 so that the rocker 237 longitudinally, will be substantially horizontal when in the middle of its rocking movement. Bearings 290 mounted to frame 33 slidably support bar 289.

The connecting link 291 operates the bar from an eccentric pin 292 on the end of the rotating shaft 293. Bearings 294 and 295 mounted on the frame 33 support the said shaft.

Speed reducer 53 operates shaft 293 by sprockets 296 and 297. Roller chain 298 operating in a cored opening in frame 33, connects the sprockets. The said chain is removed from sprocket 296 in Fig. 5.

The aforesaid housing is made dustproof at the opening in frame 33 provided for chain 298 by a cover 299 which is secured to frame 33. Flange 300 projecting outwardly therefrom is secured to a similar flange 301 provided on the end of bearing 294. A portion of the cover, bearing and its flange is illustrated broken away in Fig. 3 to expose the said opening.

During the return movement of the carriage from discharge, the rocker 237 rests on stop pin 242. Near the completion of said carriage movement, the roller 240 engages the beveled end of plate 241 causing the rocker to be lifted from said pin. The rocker is supported away from said pin by said roller during the filling operation.

The bag support is rocked by the continuously operated shaker arm 238 in an upwardly direction only and returns with it by gravitation. The 75

material is thus compacted in the filling operation by the vibrations set up by the said bag support.

Compressed air line assembly

5. The aforesaid described recess on feed pipe 14A is preferably made with a downwardly inclined bottom surface 302, Fig. 7.
- Some filling materials having adhering properties for metal, are apt to remain on said surface after a charge is discharged from the feed pipe. To remove the residue thereon, compressed air, or its equivalent, is admitted in the interval between the closing and the opening of valve 142 from the top end of the recess.
15. The top end of said recess is provided with an opening for adjusting the controller 101 and its shaft assembly. It is closed by cover plate 303 secured to side walls 103 of the recess.
20. Cover plate 303 is provided with means for distributing the said compressed air into the recess, preferably a plurality of holes 304 drilled from its bottom to connect with an air chamber 305. Holes 304 are so arranged that when air is passed through them from said chamber it will clean off the controller shaft assembly and sweep the surface 302, as indicated by the arrows, Fig. 7.
- An air cock 306 of standard design provided with an operating lever 307, is used for controlling the air to the recess. It is mounted to frame top 32 by the bifurcated bracket 308 and is operated from lever 134 by connecting link 309.
30. The air cock 306 is connected at one end with a source of compressed air; the other end is connected with the air chamber 305 in cover plate 303. Unions at the cock and cover plate are provided to facilitate repairs.
35. Some filling materials are in a heated state at the time of dropping into the feed pipe. Considerable heat is absorbed by the feed pipe from the material passing through it. In such cases the air line, preferably copper tubing 310, is tightly coiled around the feed pipe whereby the air in the tubing is heated before it reaches the air cock 302, providing dry air to the recess.
40. It will be understood that various modifications of the several parts may be made within the scope of the appended claims without departing from the invention.
45. Any device having the purpose of causing the weighed charge to discharge from the scale when operated—as lever 2, described herein—is to be construed as a charge trip device in the appended claims.
50. *What I claim is:*
1. In a filling machine having a known scale with a charge trip device that is adapted to cause the discharge of the weighed material therefrom when said device is operated, the combination of means for filling a valve bag with the said discharged material, including an ejector having a discharge orifice through which the material passes before entering the bag, a valve for closing said orifice in the interval of discharging the filled bag, means for operating the valve, means for controlling the opening of the valve, and means for automatically operating the charge trip device when the valve is opened.
  2. A bag filling machine comprising a vertically disposed feed pipe, an ejector adapted to receive the material as it gravitates through said pipe and to discharge it through a bag filling spout, a carriage having a bag support for supporting the bag in the interval of filling and for transporting it when filled to a predetermined bag discharging place, and means adapted to be automatically actuated when the ejector has discharged a predetermined amount of material for moving the carriage to said place.
  3. In a filling machine of the class described, the combination of means having a spout for filling a valve bag that is placed on the spout at the valve opening, a bag support, automatically actuated means for moving the bag support in a substantially horizontal plane from the place occupied in filling the bag, and means for removing the bag off the spout.
  4. In a machine for filling valve bags, the combination of a filling spout for directing filling material discharging through it into a valve bag suspendedly placed thereon, a carriage for supporting the bag in the interval of filling and for transporting it when filled, automatically actuated means for moving the carriage from filling position and means for removing the bag off the spout.
  5. In a filling machine having a known scale provided with a charge trip device and adapted to cause the weighed material to gravitate therefrom when said device is operated, the combination of means for filling a valve bag with the discharged material, and means controlled by said material for operating said device when the bag is filled.
  6. In a filling machine the combination of a horizontally disposed filling spout for directing filling material discharging through it into a receptacle, a support for said receptacle, a carriage carrying said support for transporting the filled receptacle away from filling position, means for automatically operating said carriage, and means for compacting the filling material in the receptacle during the interval of filling.
  7. The combination of a feed pipe, an ejector having an exterior casing provided with a discharge orifice and an intake opening connecting registrably with the outlet of said pipe, for discharging filling material gravitating from said pipe through the orifice; a valve for closing said orifice, mechanism for operating said valve, means for preventing the opening of said valve in the operative cycle of the valve operating mechanism, and means for rendering inoperative the said means.
  8. Means for filling a valve bag, a carriage for conveying the filled bag, a bag support mounted on the carriage, means adapted to engage the bag support for imparting a succession of movements to it whereby the material filling the bag is compacted, and means for discharging the filled bag from said support in the conveying movement of the carriage.
  9. The combination of a spout for directing filling material into a valve bag which is suspendedly placed thereon, a movable support for supporting the bag in the interval of filling, means for moving said support away from filling position for the purpose of discharging the filled bag, means for tilting the support after it is moved a predetermined distance, and means for causing the contents of the discharged bag to seal the valve opening when it comes to rest.
  10. In a bag filling machine, the combination of a spout carrier having a plurality of suitably spaced spouts, each of which is brought into register with an orifice in a predetermined order for the purpose of directing material discharging through the orifice into a bag, means for moving the carrier after a bag is filled to shift the next spout in order into register with said orifice,

5 a valve for closing the orifice in the interval of moving the carrier, means for closing the valve, means for opening the valve in timed relation with the movement of the carrier, and means for controlling the latter means.

11. In a machine of the class described, means for filling a valve bag, a carriage for transporting the filled bag from filling position, a bag support mounted on said carriage and adapted 10 for vibrating movement for supporting the bag in the interval of filling, and means having a member which is adapted to engage said support when the carriage is returned to filling position for imparting a succession of vibrating movements to it whereby the material filling the bag is compacted.

12. In combination, means for filling a valve bag, a bag support for supporting the bag in the interval of filling, means for tilting said support 20 to discharge the filled bag and means for contacting the lower end of the filled bag in the discharging movement for the purpose of upsetting the bag by retarding gravitation thereat, thereby causing the contents of the bag to seal 25 the valve opening when it comes to rest.

13. In a bag filling machine, a vertically disposed feed pipe, an ejector having an exterior casing for discharging material gravitating from the feed pipe through a bag filling spout, said 30 casing being adapted for the purpose described, mechanism for performing a function of the machine after the bag is filled, such as the discharge of the filled bag, said function being one of a plurality of functions constituting the operating 35 cycle of the machine and performed in a predetermined order, a clutch for operating said mechanism, a normally open electric circuit, means operatively dependent on the filling of a bag by the ejector for closing said circuit, and 40 means adapted for actuating said clutch by the closing of said circuit.

14. The combination of means for filling a valve bag with material discharging through an orifice, a spout carrier included in said means 45 and provided with two filling spouts suitably spaced apart, each of which alternately register with said orifice when the carrier is operated to direct the material into the bag, means controlled by the material before it is deposited in the bag 50 for operating the carrier when the bag is filled.

15. The structure defined in claim 14, in further combination with means for clamping the carrier after each movement to alternate the spouts.

16. The combination of a spout carrier having 55 two filling spouts suitably spaced apart, one of which is normally in register with an orifice for directing material discharging through the orifice into a bag, means for operating the carrier to alternate the spouts into register with said orifice, a valve for closing said orifice during the interval of alternating the spouts, means for automatically operating said valve, including a member which is adapted to be disengaged to 60 prevent the opening of the valve, and means for controlling the said member.

17. In a filling machine having a known scale that is provided with a charge trip device and is adapted to cause the weighed material to discharge from the scale when said device is operated, the combination of means for filling a valve bag with said material which is discharged through an orifice to the bag, a spout carrier associated with said means and provided with a 75 plurality of filling spouts suitably spaced apart,

means for operating the carrier to move the spouts in a predetermined order into register with the orifice so that one of them is in position to fill the bag previously placed thereon at the completion of each movement of the carrier, and means for operating the charge trip device in timed relation with each movement of the carrier. 5

18. The structure defined in claim 17, in further combination with means for controlling the 10 operation of the charge trip device whereby the discharge of the scale can be prevented when the carrier is operated.

19. The combination of a feed pipe, an ejector having an exterior casing provided with a discharge orifice and an intake opening registering connectedly with the outlet of said pipe for discharging filling material gravitating from the pipe through the orifice; a spout carrier having two filling spouts suitably spaced apart, one of 15 which is normally in register with said orifice to direct said material into a receptacle, means for operating the carrier to alternate the spouts into register with said orifice, a normally open valve for closing said orifice during the interval of alternating the spouts, means for operating the valve, means for preventing the opening of said valve when the inactive filling spout is shifted into register with the orifice, and means for controlling the latter means. 20

20. The combination of a spout carrier having a plurality of spaced filling spouts, one of which is normally in register with an orifice to direct material discharging through the orifice into a valve bag suspendedly placed thereon, means for 25 operating said carrier to shift each spout in successive order into register with said orifice, a bag holder for holding a bag in position on the spout that is in register with said orifice, means operated in timed relation with the movement of 30 said spout carrier for releasing the grip of the bag holder on the bag. 35

21. In a bag filling machine the combination of a spout carrier having a plurality of filling spouts, each of which is moved into register with 45 an orifice in a predetermined order for the purpose of directing material discharging through said orifice into a bag, means for operating the carrier, a bag holder for gripping a valve bag suspendedly placed on the inactive spout that is 50 next in order to be moved to filling position, a valve for closing the orifice after the bag is filled, means for closing the valve, means operating in timed relation with the movement of the carrier to shift said inactive spout to filling position for 55 opening the valve, and means for controlling the latter means by the bag holder.

22. In a valve bag filling machine, the combination of a spout carrier having two filling spouts, one of which is normally in register with 60 an orifice to direct material discharging through the orifice into a valve bag placed on the spout, the other spout being suitably spaced away to permit placing a bag in a suspended manner during the interval of filling the bag on the 65 other spout, a bag support, means for moving said support to convey the filled bag from filling position, means for operating the carrier to shift the inactive spout with a bag suspended therefrom into register with said orifice when the bag 70 support is moved from filling position, means for moving to filling position the lower end of the bag suspended from the spout shifted into register with said orifice. 75

23. The structure defined in claim 22 in fur-

ther combination with means for gripping the lower end of the bag to prevent derangement when the bag support is returning to filling position.

5 24. In a bag filling machine the combination of a vertically disposed feed pipe, a continuous operating ejector having an exterior casing for thrusting material gravitating from the feed pipe through a discharge orifice, said casing being adapted for the purpose described, a spout registrably connected with said orifice for directing the material into a valve bag threaded thereon, a bag holder for gripping the bag on the spout, a normally open valve for cutting off 10 the flow of material or dust-laden air discharging through the orifice in the interval of removing the bag off said spout, valve operating means for closing the orifice, valve operating means operating in timed relation with the valve closing 15 means for opening the orifice, and means controlled by said bag holder for controlling the latter means.

25 25. In a filling machine having a known scale with a charge trip device that is adapted to cause the weighed material to gravitate therefrom when said device is operated, the combination of means for filling a valve bag with the weighed material which passes through an orifice before entering the bag, a spout carrier associated with said means and provided with two spouts suitably spaced apart, means for operating the carrier to move the spouts alternately into register with the orifice so that one of them is in position to fill the bag previously placed thereon at the completion of each movement of the carrier, means for operating the charge trip device in timed relation with the carrier, and means for controlling the operation of the charge trip device whereby the discharge of the scale can be prevented when the carrier is operated.

40 26. In a filling machine having a known scale that is adapted to discharge the weighed material by operating a charge trip device, identified herein by the numeral 2, the combination of a feed pipe through which the material gravitates after discharging from the scale, means having an exterior casing which is provided with an intake opening connected registrably with the outlet of said pipe and a discharge orifice, for discharging said material gravitating into the casing through said orifice, a normally open valve for closing said orifice, means for operating said valve including disengageable means for opening it, means for disengaging said disengageable 45 means to prevent the opening of the valve in the operative cycle of said valve operating means, means for operating said charge trip device in timed relation with the movement of the valve opening said orifice.

55 27. The combination of means having an exterior casing for discharging filling material into a valve bag, said casing being provided with a discharge orifice and an intake opening through which the material enters, a movably supported 60 spout carrier having two filling spouts, one of which is normally in register with said orifice to direct said discharged material into a bag placed thereon, the other spout being suitably positioned to permit suspending a valve bag on it during 65 the interval of filling the other bag; means for operating said carrier to alternate said spouts into register with said orifice, means for moving the bottom end of the bag suspended from the 70 spout that is being alternated into register with 75 said orifice to filling position.

28. The combination of means having an exterior casing which is provided with an intake opening for receiving filling material and a discharge orifice, for discharging the material in a stream suitable for filling a valve bag, a spout carrier having two filling spouts, one of which is normally in register with said orifice to direct the discharged material into a valve bag suspended thereon, means for operating said carrier to alternate the said spouts into register with said orifice, a bag holder mounted on said carrier for each of said spouts, for gripping a bag placed on its respective spout, means for removing the bag holder from the bag after it is filled, means for latching said bag holder to hold it in its removed position after said removing means has completed its operative movement, a valve for closing said orifice, means for operating said valve, means for preventing the opening of said valve when the bag holder of the spout that is moved into register with said orifice is in latched position.

29. In a filling machine having a known scale that is adapted to discharge the weighed material by operating a charge trip device, identified herein by the numeral 2, the combination of a feed pipe through which the material gravitates after discharging from the scale, means having an exterior casing for discharging material from the feed pipe into a valve bag, said casing being provided with a discharge orifice and an intake 30 opening that is registrably connected with the outlet of said feed pipe, a movably supported spout carrier having two filling spouts, one of which is normally in register with said orifice to direct the discharged material into a valve bag 35 placed thereon, means for operating said carrier to bring each spout alternately into register with said orifice, a bag holder mounted on said carrier for each of said spouts for gripping a bag placed on its respective spout, means for removing the bag holder from the bag after it is filled, means for latching said bag holder to hold it in its removed position after said removing means has completed its operative movement, a valve 40 for closing said orifice, means for operating said valve, means operated in timed relation with the opening of the valve for operating the charge trip device, and means for preventing the opening of said valve when the bag holder of the spout that is moved into register with said orifice is in latched position.

30. The combination of a vertically disposed feed pipe in which a charge of filling material is deposited and allowed to gravitate through it, means having an exterior casing for discharging material from said pipe into a receptacle, said casing being provided with a discharge orifice and an intake opening which is registrably connected with the outlet of the feed pipe, a movably supported controller having a normal position which is moved and kept away from said position by the pressure of filling material of a charge dropped into said feed pipe and is adapted to return to normal position when the said pressure is reduced by the discharge of material from the feed pipe to a predetermined degree, a spout carrier provided with two filling spouts that are suitably spaced apart, one of which is in register with said orifice to direct the discharged material into a receptacle, mechanism for operating said carrier to bring each of said spouts alternately into register with said discharge orifice, means for actuating said mechanism, that is adapted to be set into operation by the movement of said controller returning to its normal position.

31. In a machine for filling valve bags, the combination of a filling spout for directing filling material into a valve bag suspendedly placed thereon, a carriage for transporting the filled bag from filling position, and means operated by the movement of the carriage for removing said bag off the spout.

32. In a bag filling machine, the combination of a horizontally disposed spout for directing material discharging through it into a valve bag which is threaded on it, a carriage for supporting the bag in the interval of filling and for transporting it when filled, means for operating the carriage, means adapted to contact the filled bag adjacent the spout for removing the bag off the spout simultaneously with the transporting movement of the carriage.

33. A bag filling machine comprising means for filling a valve bag, a horizontally disposed spout associated with said means for directing the material into a valve bag which is threaded thereon in a manner substantially as described, a carriage for supporting the bag in the interval of filling and for transporting it when filled, automatic means for operating the carriage, an arm pivotally mounted on said carriage and resiliently pressed against a stop in a substantially horizontal position, said arm being adapted to contact the valved end of the filled bag in the transporting movement of the carriage, for the purpose of removing the bag off said spout, apparatus for moving the arm to a position distant from its stop after the bag is removed from the spout, a latch for holding the arm in removed position, and means for releasing said latch when the carriage returns to filling position.

34. The combination of a vertically disposed feed pipe for receiving a charge of material, an ejector having an exterior casing provided with an intake registering with the outlet of said pipe and a discharge orifice for discharging the material gravitating into the ejector through said orifice, a spout registering with said orifice for directing the material into a bag, a carriage for supporting the bag in the interval of filling and for transporting it when filled, means controlled by the material moving past a predetermined place along its path of movement to the bag for operating the carriage.

35. A bag filling machine comprising a vertically disposed feed pipe, an ejector adapted to receive the material as it gravitates through said pipe and to discharge it through a bag filling spout, a carriage having a bag support for supporting the bag in the interval of filling and for transporting it when filled to a predetermined bag discharging place, means adapted to be automatically actuated when the ejector has discharged a predetermined amount of material for moving the carriage to said place, and means for tilting the bag support to discharge the filled bag.

36. The structure defined in claim 35 characterized in that the means for tilting the bag support is adapted to utilize the transporting movement of the carriage for its source of power.

37. A bag filling machine comprising a vertically disposed feed pipe, an ejector adapted to urge the material gravitating out of the feed pipe through a bag filling spout, a carriage for transporting the filled bag, a bag support pivotally mounted on said carriage and provided with an engagingly operated member for tilting the support, means for engagingly operating said member by the transporting movement of the car-

riage, and means adapted to be automatically actuated when the ejector has urged a predetermined amount of material through said spout for operating the carriage.

38. A bag filling machine comprising a vertically disposed feed pipe, an ejector adapted to urge the material gravitating out of the feed pipe through a bag filling spout, a carriage for transporting the filled bag, oppositely spaced side members which are suitably fixed in position for supporting the sides of the bag in the transporting movement of the carriage, a vertically adjustable bag support pivotally mounted to the carriage between said side members, means for tilting the bag support between the side members for the purpose of discharging the filled bag through the space provided between the members, and means adapted to be automatically actuated when the ejector has urged a predetermined amount of material through said spout for operating the carriage.

39. A bag filling machine comprising means for filling a valve bag, a carriage including a pivotally mounted bag support for supporting the bag in filling and for transporting it when filled to a predetermined discharging place, automatic means for operating the carriage, a fixed member suitably positioned along the path of movement of the carriage, and an arm secured to the bag support and adapted to contact the said member in the transporting movement of the carriage whereby the said support is tilted and the filled bag discharged.

40. In a filling machine the combination of a horizontally disposed filling spout for directing filling material discharging through it into a receptacle, a support for said receptacle, that is adapted for movement to transport the filled receptacle away from filling position and which is also adapted for vibratory movement to compact the material during the interval of filling the receptacle, means for causing a succession of said movements by said support, means for moving the support from filling position when said receptacle is filled, whereby the vibrating movement of the support is discontinued.

41. In a machine of the class described, the combination of means for filling a valve bag including a horizontally disposed spout for directing the material into the bag, a movably supported bag support which is adapted for movement that will compact the material filling the bag and is further adapted for movement that will cause the filled bag to gravitate from it, means for moving the bag support to discharge the filled bag and return it to filling position, means adapted to engage the bag support simultaneously with the return of said support to filling position for imparting a succession of movements to it, whereby the material filling the bag is compacted.

42. In a machine of the class described, the combination of means for filling a valve bag, a movably supported bag support which is adapted for movement that will compact the material filling the bag and is further adapted for movement that will cause the filled bag to gravitate from it, continuous operating means adapted to engage said support for the purpose of imparting a succession of movements to it whereby the material filling the bag is compacted, means for moving said support to discharge the filled bag and for returning it to filling position, by which movements the engagement of the compacting

means with the support is broken and made, respectively.

43. The combination of a filling spout for directing filling material into a valve bag placed thereon, a movable frame having a horizontally disposed bag support that is pivotally mounted to the frame at one of its ends and supported against gravity at its other end, means including a member for engaging said bag support for producing a succession of lifting movements of said bag support on its pivot during the interval of filling said bag, and means for moving said frame from filling position after the bag is filled.

44. The combination of a spout for directing filling material into a valve bag which is suspendedly placed thereon, a movable support for supporting the bag in the interval of filling, means for moving said support away from filling position for the purpose of discharging the filled bag, means for tilting the support after it is moved a predetermined distance, and means for contacting the lower end of the bag in the tilting movement to retard its gravitation, thereby causing the filled bag to fall in a manner to upset the contents of the bag for the purpose of sealing the valve opening when it comes to rest.

45. The combination of a vertically disposed feed pipe, an ejector having an exterior casing provided with an intake opening registering with the outlet of said pipe and a discharge orifice for discharging filling material gravitating into said casing through the orifice, a spout registrably connected with the orifice for directing the material into a bag, a bag support, and means operatively controlled by a charge gravitating past a predetermined place in the feed pipe for effecting the discharge of the filled bag from said support.

46. In a machine of the class described, a vertically disposed feed pipe for receiving a charge of material, an ejector for reducing the cross sectional flow of material gravitating from the feed pipe to a stream suitable for filling a valve bag, mechanism for performing a function of the machine after the bag is filled, such as the discharge of a filled bag, said function being one of a plurality of functions constituting the operating cycle of the machine and performed in a predetermined order, means controlled by said charge moving past a predetermined place along its path of movement to the bag and actuated when the ejector has filled a bag for operating said mechanism.

47. In a machine of the class described, a vertically disposed feed pipe for receiving a charge of material, an ejector for reducing the cross sectional flow of material gravitating from the feed pipe to a stream suitable for filling a valve bag, a spout for directing the stream of material into a bag, a clutch for operating mechanism after the bag is filled, such as the mechanism for discharging the filled bag, means operatively controlled by said charge moving past a predetermined place along its path of movement to the bag and actuated when the ejector has filled a bag for actuating said clutch.

48. The combination of a feed pipe, an ejector having an exterior casing provided with an intake opening registering with the outlet of said pipe and a discharge orifice for discharging filling material gravitating into said casing from the feed pipe, through said orifice; a normally open valve for closing said orifice, means operatively controlled by the material of a charge gravitating in the feed pipe, that is adapted to

operate said valve when said charge or an amount of material substantially equal to a charge has gravitated to the ejector and is discharged by it.

49. In a bag filling machine of the class described, having mechanism which constitutes an integral part of the machine and which is operated in timed relation with the filling of the bag, the combination of a vertically disposed feed pipe for receiving a charge of material having a predetermined weight or measure, an ejector having an exterior casing which is provided with an intake opening connecting with the outlet of the feed pipe for discharging material gravitating into the casing through an orifice provided in the casing, a controller which is moved from a position of rest by the said charge gravitating in said pipe and returned thereto when the ejector discharges an amount of material substantially equal to a charge through said orifice, a clutch actuated by the return movement of the controller for operating the above said mechanism.

50. The combination of a vertically disposed feed pipe in which a charge of filling material is deposited and allowed to gravitate through it, means having an exterior casing for discharging material from said feed pipe into a receptacle, said casing being provided with a discharge orifice and an intake opening which is registrably connected with the outlet opening of the feed pipe; a movably supported controller which is moved and kept from its normal position by the pressure of material of a charge deposited in said pipe and which is adapted to return to its normal position when the said pressure is reduced to a predetermined degree by discharging material from the said feed pipe, an electric circuit having means adapted for opening said circuit by the movement of said controller away from its normal position and for closing same by the movement of the controller returning to its normal position.

51. The combination of a vertically disposed feed pipe in which a charge of filling material is deposited and allowed to gravitate through it, means having an exterior casing for discharging material from said pipe into a receptacle, said casing being provided with a discharge orifice and an intake opening which is registrably connected with the outlet opening of said feed pipe; a movably supported controller having a normal position which is moved and kept away from said position by the pressure of material of a charge dropped in said feed pipe and which is adapted to return to its normal position when said pressure is reduced by discharging a predetermined amount of material from the feed pipe; a normally open valve for closing said orifice, intermittent operating means that is adapted to be set into actuation by the return movement of said controller to normal position, for closing said valve.

52. The combination of a vertically disposed feed pipe in which a charge of filling material is deposited and allowed to gravitate through it, means having an exterior casing which is provided with a discharge orifice and an intake opening which is registrably connected to the outlet opening of the feed pipe, for discharging material from said feed pipe into a receptacle, a filling spout that registers with said orifice for directing the discharged material into a receptacle, a movable support for a receptacle in process of filling, a movably supported controller having a normal position which is moved and kept away from said position by the gravitational pressure of fill-

ing material of a charge deposited in said feed pipe and which is adapted to return to normal position when the said pressure is reduced to a predetermined degree, mechanism for moving said support from filling position, means for actuating said mechanism that is adapted to be set into operation by the movement of said controller returning to its normal position.

53. The combination of a feed pipe through which filling material of a charge gravitates, an ejector having an exterior casing provided with an intake opening registering with the outlet of said pipe and a discharge orifice, for discharging filling material gravitating into said casing from the feed pipe through said orifice, a normally open valve for closing said orifice, means for operating said valve, a controller associated with said means and operatively controlled by the material of a charge gravitating in the feed pipe, 10 that is adapted to cause the actuation of said

means when the said charge or an amount of material substantially equal to a charge has gravitated to the ejector and is discharged by it.

54. In a bag filling machine, a vertically disposed feed pipe for receiving a charge of material, an ejector having an exterior casing for discharging material gravitating out of the feed pipe through an orifice, said casing being adapted for the purpose described, a spout for directing the material discharging through said orifice into a bag, a valve for closing said orifice in the interval of discharging the filled bag, means for operating the valve, a controller associated with said means and operatively controlled by the charge for timing the operation of said means, and means for removing residue material interfering with the efficient operation of the controller in the interval of discharging the filled bag. 15

ALBERT KRASA. 20
